Patented Jan. 18, 1921.

UNITED STATES PATENT OFFICE.

OSCAR J. ERICKSON, OF PORTLAND, OREGON, ASSIGNOR OF ONE-HALF TO WILLIAM A. WAGNER, OF PORTLAND, OREGON.

OIL-BURNER.

1,366,314.

Specification of Letters Patent. Patented Jan. 18, 1921.

Application filed March 25, 1920. Serial No. 368,786.

To all whom it may concern:

Be it known that I, OSCAR J. ERICKSON, a citizen of the United States, and resident of Portland, county of Multnomah, State of Oregon, have invented a new and useful Improvement in Oil-Burners, of which the following is a specification.

This invention relates to oil burners and has particularly to do with burner-heads adapted for properly mixing the oil vapors and gases with air, and spreading the resultant flame so as to obtain a high efficiency from the fuel.

The main objects of this invention are: first: to provide a burner-head of the character mentioned in which the fuel will be fully vaporized and gasified by the flame emitted from the burner; second: to provide an efficient chamber in which the vaporized and gasified oil will expand and develop a pressure head; third: to provide a mixing chamber in which the gas and vapors will be properly mixed with air; fourth: to provide a flame deflector which will spread the flame, so as to produce a high heating efficiency, and fifth: to combine the whole device in a compact form, economical in first cost, and simple in operation.

My device by which I accomplish these objects is fully shown in the accompanying drawings, in which,

Figure 1 is a front elevation of my burner;

Fig. 2 is a side elevation of the same;

Fig. 3 is a section on the line 3—3 of Fig. 2, and

Fig. 4 is a section on the line 4—4 of Fig. 1.

My burner-head comprises a one-piece hollow casting, approximately of the form of an inverted U, of which a is the bottom or base, b the parallel sides, and c the semi-circular top which connects the two sides. The casting has a cored-duct d which extends in the body as shown in Fig. 3, and forms a passage way for the fuel. A web e, integral with the sides of the body is formed with an open-ended cylindrical mixing chamber f, having a central duct g; the ends of said mixing chamber being spaced from the top and the bottom of said body.

The bottom a of the body is made with a lug h, tapped to receive a nipple i. Said lug is provided with a central hole j connecting with the duct d.

k is an elbow, and l a pipe connecting the

burner-head with the oil supply tank, (not shown).

The bottom of the burner-head is made with angular cross-section, with the vertex in alinement with the center of the opposed open end of the mixing chamber, thereby providing inclined surfaces as m, see Figs. 2 and 4, which act as baffles to deflect the flame emitted from the burner.

In the top of the burner-head is a clean-out hole closed by a pipe-plug n, and o is an orifice connecting the duct d with the atmosphere. Said orifice is in axial alinement with the mixing chamber f.

The operation of my burner-head is as follows:

Oil fed into the burner-head flows directly into the duct d. Vaporization and gasifying of the fuel will take place in this duct, and the pressure developed, will cause the jet of gas and vapor to jump the gap between the orifice o and the mixing chamber f, entering the latter and drawing with it the air required for converting the gas into a highly combustible mixture. This mixture will burn at the lower end of the mixing chamber g, and the resulting flame will impinge directly on the deflector faces m, which will serve to deflect the flame outwardly and back approximately as indicated by the broken line arrows n, in Figs. 2 and 4, thereby causing the flame to completely envelop the burner-head intensely heating the latter and promoting efficient vaporizing and gasifying of the fuel.

I claim:

A burner-head comprising a hollow body or casting in the form of an inverted U, the extremities of the legs of which are connected by a transverse base, a tubular open-ended mixing chamber parallel with and central of the legs of said U body, the hollow of the body providing a fuel passage-way having an outlet axially located with respect to said mixing chamber, the ends of the latter being spaced from the top and bottom of said body, the base of the burner head being adapted for connecting to a fuel supply, the surface of the base opposed to one end of the mixing chamber, having inclined sides the vertex of which is alined with the center of the opposed open end of said mixing chamber, whereby the flame is reflected so as to envelop the burner-head.

OSCAR J. ERICKSON.
